A. J. GRAY AND W. HEBERN.
AUTOMOBILE LOCK.
APPLICATION FILED APR. 19, 1920.

1,413,022.

Patented Apr. 18, 1922.

UNITED STATES PATENT OFFICE.

ALBERT J. GRAY AND WILLIAM HEBERN, OF OAKLAND, CALIFORNIA, ASSIGNEES, BY DIRECT AND MESNE ASSIGNMENTS, TO SECURITY AUTO LOCK CO., A COPARTNERSHIP CONSISTING OF ALBERT J. GRAY, WILLIAM HEBERN, AND DAVID GUILD, JR.

AUTOMOBILE LOCK.

1,413,022.

Specification of Letters Patent. Patented Apr. 18, 1922.

Application filed April 19, 1920. Serial No. 374,850.

To all whom it may concern:

Be it known that we, ALBERT J. GRAY and WILLIAM HEBERN, citizens of the United States, and residing in the city of Oakland, 5 county of Alameda, and State of California, have invented new and useful Improvements in Automobile Locks, of which the following is a specification.

The present invention relates to a lock for 10 automobiles of a certain type having universally movable gear shift levers, and resides in the provision of a relatively simple, inexpensive, and reliable lock which may be easily installed without necessitating any 15 change in the construction of the automobile, and, which, when locked, will prevent movement of the gear shift lever out of neutral position, whereby the automobile is inoperative and safe-guarded against theft.

20 An object of the invention is to provide a lock of the character described, which is at all times in a position to be readily locked in neutral position, there being a spring for normally holding the lock out of position 25 whereby the lever may be freely operated, the locking being effected by moving the lock downwardly into a predetermined position and then turning the key.

The invention possesses other advantages 30 and features, some of which, with the foregoing, will be set forth at length in the following description wherein we shall outline in full that form of the invention which we have selected for illustration in the drawings accompanying and forming a part of 35 the present specification. In said drawings, we have shown one form of the construction of our invention, but it is to be understood that we do not limit ourselves to such form, 40 since the invention as expressed in the claims may be embodied in a plurality of forms.

Figure 1 is a fragmentary perspective view 45 of an automobile, showing the lock of our invention as when locked.

Figure 2 is an enlarged fragmentary side elevation, partly in section, of the lever and its connection with the casting in which it works, showing the lock in unlocked position in full lines, and in locked position in dotted 50 lines.

Figure 3 is a bottom plan view of the movable locking member.

Figure 4 is a top plan view of the stationary locking member.

Figure 5 is a sectional view taken on the 55 line 5—5 of Figure 4.

Figure 6 is a fragmentary vertical sectional view illustrating the locking lugs and their co-operating mechanism in detail.

Figure 7 is an enlarged fragmentary vertical section showing in detail the means for frictionally holding the locking member in up-position on the gear shift lever.

Referring particularly to the drawings, 7 designates the gear shift lever of an automobile, said lever being of the universal movement type and mounted in the customary manner in a casting 8.

Automobiles of the make with which our invention is to be used employ a screw 70 threaded ring, not shown, which ring is mounted in the casing 8 to retain the lever 7 in place. To adapt automobiles of this type for use of our invention, we remove the ring and substitute therefor a ring 9 which is 75 externally screw threaded, as at 10, and turned into the screw threaded opening 11, in the casting 8. This ring 9 retains the lever 7 in place and is also constructed to provide for locking of the lever. In this 80 connection, it is to be noted that the ring 9 is provided with a laterally extending annular flange 12 upon its upper end, which flange engages upon the top of the casting 8 and upon its outer end is curved downwardly, as at 13, so as to conform to, and closely engage said casting. Fixed upon the flange 12 at opposite points are upwardly extending locking lugs 14, each of which are undercut by being laterally grooved as at 15, 90 so as to provide the locking shoulder 16. This ring 9 with its component parts constitutes the stationary locking member of the invention.

The movable locking member comprises 95 a plate 17 preferably of circular form, provided with a central aperture 18 for reception of the lever 7. The plate 17 is mounted upon the lever by removing the ball handle portion 19 from the upper end of the lever 7 and inserting the lever through said opening 18, said plate slipping downwardly upon said lever so as to co-operate with the stationary locking member.

The plate 17 is provided on opposite sides with horizontal openings 20 extending from the outer edges thereof to the aperture 18. Slidably mounted in each opening is a pin 21, one end of which is adapted to engage the lever 7. The other ends of these pins are enlarged and the outer ends of the enlarged portions are engaged by expansion springs mounted in the openings and held in place by screw plugs 22'. These springs tend to force the pins into yielding engagement with the lever 7 and as the lever 7 increases in diameter gradually towards its lower end, the frictional engagement by the pins will be sufficient to hold the movable locking member normally in up and out-of-the-way position. However, the locking member may be readily moved downwardly by applying pressure to the upper side thereof, said pressure tending to force the pins inwardly against the action of the springs so as to allow said member to be pushed downwardly.

The plate 17 carries a suitable lock 23, an operating member 24 of which is movable in an arc and extends into an arcuate slot 25 formed in an arcuate locking bolt 26. This bolt 26 is slidably mounted within a recess 27 formed in the upper side of the plate 17 and at its free ends is provided with lugs 28 adapted to extend into the grooves 15 under the shoulder 16 of the lugs 14 so as to lock the movable locking member upon the stationary locking member. The bolt 26 is provided with slots 28' through which extend screws 28'', said screws entering the plate 17 and serving to hold the arcuate bolt 26 slidably in place on said plate.

A suitable key 29 may be provided for actuation of the lock 23 and by inserting the key in the lock and moving it in the proper direction, the arcuate bolt 26 may be moved back and forth laterally into and out of position as desired.

It will thus be seen that the lock is normally disposed so as not to interfere with the operation of holding the movable locking member in out-of-the-way position. To lock said gear shift lever against operation out of its neutral position, the plate 17 is moved downwardly and the lugs 14 will extend into recesses 30 formed in the under side of the plate 17, said plate resting upon the ring 9 and closely surrounding it. The recess for the sliding bolt opens at its ends into the recesses 30 so that the lugs 28 will extend into said recesses and engage under the shoulders 16 on the lugs 14. This operation of the locking elements may be effected after the movable locking member has been so moved into the position against the action of the spring pressed open, by use of the key 29 as hereinbefore explained.

With reference to the foregoing descrip-

tion and the accompanying drawings, it will be observed that we have provided exceptionally simple and highly efficacious locking means, which when locked, will reliably hold the gear shift lever against operation and which in itself is not subject to derangement by being tampered with. One of the most essential features of the invention is the provision of a lock which can be readily incorporated in the automobile for use thereon without necessitating any change in the construction of the automobile, and which is at all times readily accessible from the driver's seat and in position to be quickly locked.

We claim:

1. The combination with the gear shift lever of an automobile and a member on the automobile to which said lever is attached, of locking lugs carried by said member and having recesses therein, a movable locking member vertically movably mounted upon the gear shift lever and having recesses therein adapted to receive said locking lugs, means for holding said locking member out of contact with said lugs, and means for locking said locking member in contact with said lugs comprising a locking device having a bolt the ends of which are movable into and out of said recesses in the lugs.

2. The combination with the gear shift lever of an automobile and a member on the automobile to which said lever is attached, of locking lugs carried by said member and having recesses therein, a movable locking member vertically movably mounted upon the gear shift lever and having recesses therein adapted to receive said locking lugs, means for holding said locking member out of contact with said lugs, and means for locking said locking member in contact with said lugs comprising a locking device having a bolt movable into and out of said recesses in the lugs, said bolt being arcuate and having the ends thereof disposed for entering said recesses in the lugs.

3. In combination with the gear shift lever of an automobile, a member in which said lever is mounted, said member having a screw threaded opening therein surrounding said lever, of an annular locking member spaced circumferentially from said lever and having a screw threaded portion screwed into said opening, lugs on said locking member, a locking member vertically movably mounted upon but free from any connection otherwise with said lever, and having recesses to receive said lugs, means for normally holding said member out of contact with the lugs, and means for locking said member in contact with said lugs.

4. The combination with a gear shift lever of an automobile, a member in which

said lever is mounted, said member having a screw threaded opening therein surrounding said lever, of a locking member provided with a screw threaded portion 5 screwed into said opening, a locking member vertically adjustably mounted upon said member, means for normally holding said

movable locking member out of locking position and means for locking said members to one another to prevent movement of 10 said lever which means is free from connection with said lever.

ALBERT J. GRAY.

WILLIAM HEBERN.
